UNITED STATES PATENT OFFICE

2,626,718

PARKING SYSTEM

Ihno F. Weber, Dayton, Ohio

Application April 19, 1949, Serial No. 88,345

6 Claims. (Cl. 214—16.1)

1

This invention relates to a built up structure in which automobiles can be parked.

It is the general conception that a complete garage building shall be provided for the purpose of parking automobiles off the street. However, such complete buildings are expensive to construct, and are wasteful of parking area because of the large amount of space required for ramps and driveways in the building.

Even such open-air structures as have been provided in the past are primarily no different from the usual buildings except that the side walls have been eliminated to form an open-air structure. However, even here it is necessary to have the usual ramps extending between the various floors of the building and driveways to take care of the movement of cars through the structure.

It is, therefore, the object of this invention to provide a built up structure that will conserve parking space and in which the automobiles can be parked side by side in parallel rows one behind the other without any provision for movement of cars between the various rows.

It is still another object of this invention to provide a built up structure for the parking of automobiles on several floor levels in which the automobiles can be placed in a specific space on any floor level without requiring any reshifting of the automobiles that have already been parked in the structure.

It is still another object of this invention to provide a skeleton type of structure in which automobiles can be parked at various levels, the skeleton type of structure greatly reducing the cost of producing the same.

It is still another object of this invention to provide a system and apparatus for parking of automobiles wherein the automobiles are moved automatically into a selected space on a selected floor, thus eliminating the necessity of the great number of attendants for parking of the automobiles.

Still another object of this invention is to provide a system and apparatus for parking of automobiles wherein the several floor levels of a built up structure in which the automobiles are parked each consist of a plurality of movable platforms that are adapted to receive the automobiles, and which platforms can be moved into selected positions to place selected parking spaces in a predetermined position to receive automobiles from an elevator operating between the various levels of the structure.

Further objects and advantages will become

2

apparent from the drawings and following description.

In the drawings:

Figure 1 is a vertical elevational view of a side of a built up structure constructed in accordance with this invention.

Figure 2 is a plan view of one of the floor levels of the structure.

Figure 3 is an enlarged perspective elevational view of a portion of the structure to illustrate in more detail the mechanical arrangement of the structure.

Figure 4 is a plan view of a car carrier that carries the automobiles and moves them into and out of the parking space in the structure.

Figure 5 is an elevational side view of the car carrier shown in Figure 4.

Figure 6 is an elevational view of a portion of the structure illustrating the apparatus for operating the car carrying platforms.

Figure 7 is a diagrammatic illustration of a hydraulic system for operating the car lifting mechanism provided on the car carrier shown in Figures 4 and 5.

Figure 8 is a schematic wiring diagram of a control system for the apparatus.

In this invention there is provided a built up skeleton-like structure consisting of a plurality of floor levels that is adapted to receive automobiles for parking. The various floor levels or parking levels are spaced vertically one from another only a sufficient height to permit the automobiles to be moved into and out of at various parking levels. Thus, considerable space is saved as well as considerable height and building materials.

On the various parking levels of the built up structure there is provided on each of the levels a plurality of platforms that are movable transversely of the structure. These platforms are each adapted to receive several automobiles which when once placed on the platforms remain in place until the automobile is to be delivered to the owner.

The platforms are adapted to be moved relative to a central aisle in the structure to bring the several parking spaces into alignment with the loading aisle so that automobiles can be placed in the various parking spaces on the several platforms selectively by merely advancing the automobiles down the loading aisle.

An elevator is provided in the structure for carrying the automobiles to the various parking levels and for returning them to the floor level. It is the purpose of the invention to provide a

built up structure for parking automobiles that uses the cubical space of the structure to the fullest extent. Further, the structure is provided with no internal walls, but the interior of the structure is a steel skeleton framework, thereby reducing construction costs to a minimum. However, if desired, a suitable roof can be placed over the structure and sheet metal side walls can be secured for the outer walls of the structure for the purpose of enclosing the parked automobiles to keep them out of the weather.

The built-up structure consists of a plurality of vertical risers 10 that are arranged in parallel rows transversely of the structure and longitudinally thereof, as shown in Figure 2. The vertical risers 10 are preferably steel I beams and form the main supports for the structure. Extending between each of the risers 10 from front to rear of the structure are a plurality of I beams 11. These I beams 11 are secured to the risers 10 by means of gusset plates 12 in a convenient or conventional manner. Extending transversely of the structure on each side of the risers 10 are the rails 13. Rigidity of the structure is thereby established by the I beam supports and the rails 13.

The rails 13 also provide the support for the automobile receiving platforms 15. These platforms 15 are each adapted to receive several automobiles and are movable from side to side of the structure for the purpose of aligning the several spaces 15-A, 15-B, 15-C, 15-D and 15-E with an elevator 16 whereby an automobile can be moved from the elevator into the selected space positioned in front of the elevator.

Each of the platforms 15 consists of a plurality of parallel and horizontally disposed supporting beams 17. Each of these supporting beams 17 is provided with a flanged wheel 18 carried at each end thereof that rests on the transverse rails 13 that extend across the structure at each end of the support beams 17, shown in Figures 2 and 3.

The supporting beams 17 are inter-connected by channels 19 that extend transversely of the supporting beams 17 to thereby tie the several supporting beams 17 into a platform unit which can be moved as a unit transversely of the structure while supported on the rails 13. The upper face of the supporting beams 17 can provide a catwalk.

Positioned alongside of the supporting beams 17 there is a rail 20 that may be carried on the channels 19. These rails 20 are provided with a pocket or recess 21 adapted to receive the front or rear wheels of an automobile when it is in position on the platform to prevent the automobile from rolling in one direction or another on the platform.

Between each of the cooperating rails 20 adjacent the supporting beams 17 which receive the automobile, as shown in Figure 3, there is provided a pair of rails 22.

As shown in Figure 2 the pairs of rails 22 provided on the platforms 15 are all adapted to align one with the other when the platforms are in their normal positions, these pairs of rails 22 are also adapted to align with a pair of rails 23 carried on the elevator 16 provided within the elevator shaft 25.

On the elevator 16 there is provided a car carrier 30 illustrated in Figures 4 and 5. This car carrier is supported on the pair of rails 23 on the elevator 16 and is adapted to lift the automobile from engagement with the elevator and to carry

the automobile forward into one of the spaces on one of the platforms in the structure.

In Figure 7 there is a diagrammatic illustration of the hydraulic system used in the car carrier 30. In this diagrammatic system the hydraulic pump 43 draws liquid from the reservoir 45 through the suction pipe 46 and discharges it through the pipe 47 into the hydraulic motor 42. Movement of the piston 48 forwardly will cause the lift mechanism to operate to raise an automobile.

A return line 50 is provided between the hydraulic motor 42 and the reservoir 45, a solenoid operative valve "S" being provided in the line 50 to allow free flow of hydraulic fluid from the motor to the reservoir when the valve is open, and thereby permit the automobile to be lowered, in a manner hereinafter described.

Independent electric motors 60 are provided for driving the several platforms 15 to move them transversely of the structure. The motors 60 are suitably mounted on the structure beneath the various platforms. Each of the motors 60 carry a drum 61 on the drive shaft thereof over which a cable 62 passes.

The cable 62 extends between pulleys 63 and 64 positioned at opposite sides of the structure. The cable is attached to the platform 15 by a fastening device 66 having a turnbuckle connection 65 to tighten the cable.

Rotation of the drum 61 in one direction will cause the platform to move in one direction on the rails 13, and reverse rotation of the drum 61 will cause the platform to move in a reverse direction.

The car carrier 30 may consist of the car frame 31 having pairs of wheels 32 and 33 at each end thereof that engage the rails 23 of elevator 16. The wheels are flanged to prevent the car carrier from jumping off the rails.

On the car carrier 30 there is provided an electric motor 34 that may be driven in either direction of rotation for moving the car carrier forward and backwardly. The motor 34 is connected by means of a chain drive 35 with the axle of the pairs of wheels 32 and 33.

Also carried on the car carrier 30 is a hydraulic lifting device for raising the automobile from the elevator so that it will be carried fully by the car carrier. This lifting device may consist of a pair of parallel arms 36 and 37 provided at each end of the car carrier 30. These arms have a supporting member 38 inter-connecting them. On the arms 36 and 37 are gear segments 39 and 40 that engage a rack 41. The rack 41 is connected to a hydraulic motor 42 through the connecting rod 49 whereby forward and rearward movement of the rack 41 through the hydraulic operation of motor 42 will raise or lower the lifting mechanism. A hydraulic motor 42 is provided at each end of the car carrier 30 for operating the respective lift mechanisms at the respective end of the car carrier.

The hydraulic motors 42 are supplied with fluid under pressure by means of a pump 43 which is driven by the electric motor 44. A reservoir 45 is provided for supplying the pump 43.

In the arrangement of the structure, a central loading aisle 100 is free of automobiles at all times, the platforms on any one level all having their end portions in alignment to form the loading aisle. This loading aisle and the rails therein are in alignment with the rails 23 on the elevator 16. Also when any one of the platforms 15 are moved relative to the loading aisle 100

the rails 22 of any space on the platform aligns with the other rails in the loading aisle. Thus, the car carrier 30 can move from the elevator 16 along the loading aisle 100 to deposit a car in any space on any platform according to a pre-selection of the platform to be used and the space to be filled.

As shown in Figure 1 the platforms alternate from the left to the right hand side of the structure from one parking level to another to balance the structure. However, since the platforms extend on both sides of the loading aisle any two parking levels form a complete utilization of space for the parking of automobiles, the loading aisle 100 being the only unoccupied space in any part of the platform structure.

As will be seen from the arrangement illustrated in Figures 1 and 2, the minimum working space for each platform comprises a space equal to at least twice the parking spaces on the movable platform for automobiles, less one. This arrangement permits the back-and-forth movement of each parking platform and provides for one space, which is ordinarily unoccupied, for utilization during transfer of an automobile from the elevator 16 to a parking space on an adjacent platform.

Operation

The sequence in the general operation of the parking system and apparatus is such that an automobile can be placed in position on the elevator of the building.

When the automobile is placed on the elevator, the hydraulic system of the car carrier will be actuated to lift the car from the elevator and support it upon the car carrier.

The operator will make a selection of the floor to which the elevator will rise and will also select the platform and the space on the platform that is to receive the automobile.

The operator will then cause the control circuit to function whereby to cause the elevator to rise to the selected floor.

During the time the elevator is rising to the selected floor, the selected platform on the floor moves to place the particular space in position to receive the automobile when the elevator arrives at the floor.

When the elevator arrives at the selected floor, the car carrier will move forward to place the automobile in the selected position on the selected platform. When the car is positioned in its place on the platform, the hydraulic system of the car will be actuated to allow the automobile to drop onto the platform in its selected space.

When the automobile drops into its selected space on the platform, the car carrier will be returned to the elevator. When the car carrier returns to the elevator, the elevator will be actuated to return to the ground floor ready to receive another automobile.

The control circuit for automatically obtaining this sequence of operations is shown in Figure 8.

In the schematic electric circuit of Figure 8, M represents the electric motor for operating the pump of the hydraulic system on the car carrier. EM is the elevator motor for raising and lowering the elevator between the floors of the building. CM is the car carrier motor for moving the car carrier to and from the elevator. PM represents the several motors that move the platforms on the respective floors.

In the electric circuit only sufficient elements have been shown to complete a cycle of operation

of the parking system, but it is understood that additional units can be provided to take care of various floors of the building.

When an automobile is moved onto the elevator and positioned over the car carrier on the elevator, the switch A is closed to make circuit to the car carrier motor M from the power line X to the power line Y through the lines 10, 11 and 12. The interlock switch B is closed at this time. Concurrently, current is carried to the relay coil C to close the holding relay D so that when the pump motor M causes operation of the hydraulic car lift and the switch A is opened, the motor will continue to operate the pump until the limit switch E is opened, whereupon the pump motor will stop with the automobile supported on the car carrier in elevated position.

The operator can at that time, or previously, make the selection of the floor to which the automobile will be sent and of the platform and space on the platform to which it will be delivered. The operator closes one of the floor selector switches F, one of the platform selector switches G for that particular floor and one of the space selector switches H for that particular platform. For example, floor selector switch F2 is represented as being closed by the dotted arrow through it to select the second floor, platform selector switch G2 is represented as being closed to select the second platform on the second floor and space selector switch H3 has been closed to select the third space on the second platform on the second floor.

With the selection thus made, the operator will close the starting button S which momentarily makes circuit between power lines X and Y through the lines 13, 14, and 15, switch F2, and the forward starting relay I. Concurrently, current is supplied to the holding relay coil J to close the contacter J1 upon the lower contacts and thus establish a holding circuit through the starting coil I until the elevator reaches the selected second floor at which time the floor limit switch K2 will open to break the circuit through the starter I and the relay coil J, thus stopping the elevator at the second floor. Similar limit switches K1 and K3 are in series with the floor selector switches F1 and F3.

When the holding relay J is energized during the "up" movement of the elevator, the circuit through the upper contacts of the holding coil is broken to prevent actuation of the car carrier motor while the elevator is moving.

The car carrier motor CM is energized by operation of the one way acting switch L which when the arm 16 is rotated counter-clockwise closes the switch, and when operated clockwise, causes no operation of the switch L. The switch L is located on the elevator and is tripped as it reaches the various floors. Thus, so long as the elevator is in motion and the relay coil J is energized to retain the elevator in motion, the tripping action of the switch L will not effect operation of the car carrier motor to cause it to move forward off of the elevator.

The switch L will be delayed in its closed position for a short interval after tripping the same by the time delay device 17. This allows sufficient time to cause the car motor CM to begin its forward movement off of the elevator. Promptly upon forward movement of the car motor CM as caused by closing of the circuit through the lines 18, 19 and 20 through the forward starting control N, the forward limit switch O will be closed. This energizes the holding relay coil P

through the lines 19 and 22, relay coil P and lines 23 and 24. The relay Q is then closed to establish a holding circuit through the lines 18 and 22 to the forward starting control N of the car motor CM to keep the car motor in forward motion until the limit switch O is opened mechanically by engagement with a mechanical part of the platform selected to receive the automobile.

When the car motor moves the car carrier to its position over the selected platform to receive the automobile, switch R is closed to energize the solenoid operated valve S to open the same and release the hydraulic lift system on the car carrier to permit the lift system to drop the automobile onto the platform, a selected platform having previously been placed in a selected position to receive the automobile in a manner hereinafter described.

When the automobile drops to the platform the double switch T is operated to close the contacts U and open the contacts B. The closing of the contacts U establishes an electric circuit to the reverse starter control W for the car motor CM through the lines 25, 26, 27 and 28. Concurrently, a circuit is established through a relay coil AA through the lines 26, 29 and 28 to close the relay BB. This establishes a holding circuit to the reverse starting control W for the car motor CM.

When the automobile is dropped to the platform the switch A is closed, which would tend to start the hydraulic lifting system on the car carrier, if it were not for the fact that the interlock switch B is now open to prevent a circuit being made through the pump motor M.

Reverse operation of the car carrier motor CM will return the car carrier to the elevator. When the car carrier is on the elevator the switch CC will open to stop the car carrier motor CM.

As the car carrier motor reaches its position on the elevator the one way acting switch DD will be operated to momentarily close the contacts DD-1 to establish a circuit through the reverse starter control II for the elevator motor EM. Concurrently, an electric circuit is made through the relay coil EE to close the relay FF thereby establishing a holding circuit through the reverse starter control II for the elevator motor EM which will return the elevator to the first floor whereat the limit switch GG will be opened to break circuit through the holding circuit of the reverse control II and thereby stop the elevator motor.

To place a selected platform on a selected floor in a selected position the platform selector switch G has previously been closed as well as the space selector H-3 for the platform motor PM-2, as previously described. After the closing of the selector switch the time delay switch HH is closed manually by the operator which thereby establishes a circuit through the forward starting control JJ of the starter for the platform motor PM-2 through the lines 30, 31, 32, 33, 34 and 35. The time delay switch HH is so constructed and timed to maintain a circuit through the starting control JJ for sufficient time to allow the maximum movement of the platform. When the platform reaches its selected forward position the limit switch KK-3 in series with the space selector H-3 will be open to stop the platform at the selected space.

After the automobile has been placed upon the platform in the selected space and the car carrier has returned to the elevator in the man-

ner previously described, and the elevator has started its "down" movement, the one way acting switch LL will be operated by the "down" movement of the elevator to momentarily close the contacts LL-1. This makes a circuit through the return starting control NN for the platform motor PM-2 to start the platform to return to its initial position. Concurrently, a circuit is made through the holding coil OO through the lines 36, 37, 38, 29 and 40 to close the relay PP and thereby retain circuit to the return control NN for the platform motor PM-2 until it returns to its initial position, at which the limit switch QQ will open to break circuit to the holding relay coil OO and de-energize the starting control NN to stop the platform motor PM-2.

Incidentally, when circuit is made to the reverse starting control NN of the platform motor PM-2, similar circuit is made to the other platform motors PM-1 and PM-3 to assure that these platforms will be in their starting position and to return them in the event they might not have been returned previously due to some faulty operation.

While the apparatus disclosed and described herein constitutes a preferred form of the invention, yet it will be understood that mechanical alterations can be made to the apparatus without departing from the spirit of the invention, and that the modifications that fall within the scope of the appended claims are intended to be included herein.

Having thus fully described my invention, what I claim as new and desire to secure by Letters Patent, is:

1. A built up automobile parking structure which includes, a skeleton structure having a plurality of horizontally positioned parking levels, each of said parking levels comprising a plurality of platforms each having a plurality of parking spaces thereon which to place automobiles in side by side relationship longitudinally of the said platform, said platforms on the respective levels being movable horizontally in a path parallel to other platforms on the same level, the said parking spaces on said platforms being longitudinally in alignment with one another whereby to park automobiles on adjacent platforms in end to end relationship, each of said platforms operating in a minimum working space for shifting of the platform equal to twice the parking spaces arranged on the platform, less one, one of said parking spaces being an aisle space across which an automobile can be moved from one platform to another, means individually moving the said platforms to place a parking space in alignment with the aisle space of an adjacent platform, and an elevator in longitudinal alignment with the aisle spaces of the platforms at the various parking levels, a transfer car movable onto said elevator and movable therefrom over the aligned aisle spaces, control means for selecting a particular parking space in a particular platform at a particular parking level including, means for rendering said control means active to cause the selected platform on the selected level to place the selected parking space in alignment with the loading aisle of the selected level, control means for causing said elevator to rise to the selected level, control means actuated in response to the arrival of the elevator at the selected level to actuate the said transfer car to advance the same to the selected parking space on the selected platform,

control means actuated in response to the arrival of the transfer car at the selected space for causing said transfer car to drop the car onto said platform into its parking space, control means actuated in response to the placing of the car on the platform for causing return of the transfer car onto the elevator, and control means actuated in response to the return of the transfer car onto the elevator for causing the elevator to return to its starting position.

2. An automobile parking structure which includes, a structure having a plurality of parking levels, each of said levels comprising a plurality of platforms movable in parallel adjacent paths through said structure, said platforms each consisting of a plurality of parking spaces arranged for parking of automobiles therein in side by side relationship longitudinally of the platforms, each of said platforms operating in a minimum working space for shifting of the platform equal to twice the parking spaces arranged on the platform, less one, one of said parking spaces being alignable with other like spaces on adjacent platforms forming therewith a loading aisle extending across the several platforms in the respective parking level, an elevator for raising and lowering automobiles relative to the several parking levels positioned longitudinally in alignment with the said loading aisle spaces when in alignment, the said loading aisles of various parking levels being positioned vertically one above the other, a transfer car movable onto said elevator and movable therefrom over aligned loading aisle spaces and parking spaces aligned therewith, track means in the loading aisle space of each of said platforms to receive said transfer car whereby to move an automobile across said loading aisle space on any platform, corresponding track means in each of said parking spaces on said platforms alignable with the track means in said loading aisle spaces whereby to receive said transfer car thereon, said transfer car including drive means thereon for moving the same from the elevator over said track means longitudinally along the loading aisle spaces to place an automobile in a parking space on a platform aligned therewith, control means for selecting a particular parking space in a particular platform at a particular parking level including, means for rendering said control means active to cause the selected platform on the selected level to place the selected parking space in alignment with the loading aisle of the selected level, control means for causing said elevator to rise to the selected level, control means actuated in response to the arrival of the elevator at the selected level to actuate the said transfer car to advance the same to the selected parking space on the selected platform, control means actuated in response to the arrival of the transfer car at the selected space for causing said transfer car to drop the car onto said platform into its parking space, control means actuated in response to the placing of the car on the platform for causing return of the transfer car onto the elevator, and control means actuated in response to the return of the transfer car onto the elevator for causing the elevator to return to its starting position.

3. An automobile parking structure which includes, a structure having a plurality of parking levels, each of said levels comprising a plurality of platforms movable in parallel adjacent paths through said structure, said platforms each consisting of a plurality of parking spaces ar-

ranged for parking of automobiles therein in side by side relationship longitudinally of the platforms, each of said platforms operating in a minimum working space for shifting of the platform equal to twice the parking spaces arranged on the platform, less one, one of said parking spaces being alignable with other like spaces on adjacent platforms forming therewith a loading aisle extending across the several platforms in the respective parking level, an elevator for raising and lowering automobiles relative to the several parking levels positioned longitudinally in alignment with the said loading aisle spaces when in alignment, the said loading aisles of various parking levels being positioned vertically one above the other, a transfer car movable onto said elevator and movable therefrom over aligned loading aisle spaces and parking spaces aligned therewith, track means in the loading aisle space of each of said platforms to receive said transfer car whereby to move an automobile across said loading aisle space on any platform, corresponding track means in each of said parking spaces on said platforms alignable with the track means in said loading aisle spaces whereby to receive said transfer car thereon, said transfer car including drive means thereon for moving the same from the elevator over said track means longitudinally along the loading aisle spaces to place an automobile in a parking space on a platform aligned therewith and further including additional means to raise and lower an automobile relative to said platform, control means for selecting a particular parking space in a particular platform at a particular parking level including, means for rendering said control means active to cause the selected platform on the selected level to place the selected parking space in alignment with the loading aisle of the selected level, control means for causing said elevator to rise to the selected level, control means actuated in response to the arrival of the elevator at the selected level to actuate said transfer car to advance the same to the selected space, control means actuated in response to the arrival of the transfer car at the selected space for causing said transfer car to drop the car onto said platform into its parking space, and control means actuated in response to the placing of the car on the platform for causing return of the transfer car onto the elevator.

4. An automobile parking structure which includes, a structure having a plurality of parking levels, each of said levels comprising a plurality of platforms movable in parallel adjacent paths through said structure, said platforms each consisting of a plurality of parking spaces arranged for parking of automobiles therein in side by side relationship longitudinally of the platforms, each of said platforms operating in a minimum working space for shifting of the platform equal to twice the parking spaces arranged on the platform, less one, one of said parking spaces being alignable with other like spaces on adjacent platforms forming therewith a loading aisle extending across the several platforms in the respective parking level, an elevator for raising and lowering automobiles relative to the several parking levels positioned longitudinally in alignment with the said loading aisle spaces when in alignment, the said loading aisles of various parking levels being positioned vertically one above the other, a transfer car movable onto said elevator and movable therefrom over aligned

loading aisle spaces and parking spaces aligned therewith, means connected with said platforms individually operating each of said platforms to position a parking space thereof in alignment with the loading aisle spaces of adjacent platforms and with said elevator, and a control system for automatically controlling the parking of an automobile including, means for actuating the transfer car to cause the same to support an automobile placed thereover, control means for selectively operating a platform at a selected parking level to position a selected parking space in alignment with the loading aisle, means for selectively causing the elevator to carry the automobile to a selected parking level, control means for causing said transfer car to remove the automobile from the elevator and place it in the selected parking space and return to the elevator, and control means for returning the elevator to its starting position.

5. An automobile parking structure which includes, a structure having a plurality of parking levels, each of said levels comprising a plurality of platforms movable in parallel adjacent paths through said structure, said platforms each consisting of a plurality of parking spaces arranged for parking of automobiles therein in side by side relationship longitudinally of the platforms, each of said platforms also having a space alignable with other like spaces on adjacent platforms forming therewith a loading aisle extending across the several platforms in the respective parking level, an elevator for raising and lowering automobiles relative to the several parking levels positioned longitudinally in alignment with the said loading aisle spaces when in alignment, the said loading aisles of various parking levels being positioned vertically one above the other, a transfer car movable onto said elevator and movable therefrom over aligned loading aisle spaces and parking spaces aligned therewith, means connected with said platforms individually operating each of said platforms to position a parking space thereof in alignment with the loading aisle spaces of adjacent platforms and with said elevator, control means for selecting a particular parking space in a particular platform at a particular parking level including, means for rendering said control means active to cause the selected platform on the selected level to place the selected parking space in alignment with the loading aisle of the selected level, control means for causing said elevator to rise to the selected level, control means actuated in response to the arrival of the elevator at the selected level to actuate the said transfer car to advance the same to the selected parking space on the selected platform, control means actuated in response to the arrival of the transfer car at the selected space for causing said transfer car to drop the car onto said platform into its parking space, control means actuated in response to the placing of the car on the platform for causing return of the transfer car onto the elevator, and control means actuated in response to the return of the transfer car onto the elevator for

causing the elevator to return to its starting position.

6. An automobile parking structure which includes, a structure having a plurality of parking levels, each of said levels comprising a plurality of platforms movable in parallel adjacent paths through said structure, said platforms each consisting of a plurality of parking spaces arranged for parking of automobiles therein in side by side relationship longitudinally of the platforms, each of said platforms also having a space alignable with other like spaces on adjacent platforms forming therewith a loading aisle extending across the several platforms in the respective parking level, an elevator for raising and lowering automobiles relative to the several parking levels positioned longitudinally in alignment with the said loading aisle spaces when in alignment, the said loading aisles of various parking levels being positioned vertically one above the other, a transfer car movable onto said elevator and movable therefrom over aligned loading aisle spaces and parking spaces aligned therewith, means connected with said platforms individually operating each of said platforms to position a parking space thereof in alignment with the loading aisle spaces of adjacent platforms and with said elevator, control means for selecting a particular parking space in a particular platform at a particular parking level including, means for rendering said control means active to cause the selected platform on the selected level to place the selected parking space in alignment with the loading aisle of the selected level, control means for causing said elevator to rise to the selected level, control means actuated in response to the arrival of the elevator at the selected level to actuate said transfer car to advance the same to the selected space, control means actuated in response to the arrival of the transfer car at the selected space for causing said transfer car to drop the car onto said platform into its parking space, control means actuated in response to the placing of the car on the platform for causing return of the transfer car onto the elevator, control means actuated in response to the return of the transfer car onto the elevator for causing the elevator to return to its starting position, and control means actuated in response to the down movement of the elevator for causing the selected platform to return to its starting position.
